CLAIM

The ornamental design for a one-button toothbrush handle, as shown and described.

DESCRIPTION

1. One-button toothbrush handle
Fig. 1.1 is a front, side and perspective view of an electric toothbrush showing our new design;
Fig. 1.2 is a front elevation view thereof;
Fig. 1.3 is a rear elevation view thereof;
Fig. 1.4 is a right side elevation view thereof;
Fig. 1.5 is a left side elevation view thereof;
Fig. 1.6 is a top plan view thereof;
Fig. 1.7 is a bottom plan view thereof.

(Continued)

The broken lines shown in the figures depict portions of the article that form no part of the claimed design.

1 Claim, 4 Drawing Sheets
